PORTABLE IRONING DEVICE

Allan L. Briggs, Jamestown, N. Y., assignor to
 Jamestown Metal Equipment Company, Inc.,
 Jamestown, N. Y., a corporation of New York

Application June 28, 1944, Serial No. 542,542

11 Claims. (Cl. 38—60)

1

This invention relates to an improved laundry device and more particularly to an ironer of the type employing a roller pad and adjustable heated shoe.

More specifically the invention is directed to, and has for one of its objects, the provision of an ironer of such proportions as to be readily portable and usable when placed on any convenient bench, stand, or table. Another object of the invention lies in the provision of an ironer of the portable type in which certain of the operative parts, such as motor, drive mechanism, etc., are contained within the ironer base. A further object of the invention lies in the provision of a portable ironer, in the base of which lubrication means is so located as to obviate any necessity of frequent oiling of the motor and the drive mechanism connected therewith. Another and important object of the invention lies in the provision of an ironer base, the top of which is forwardly inclined, and by reason of which the ironer roll and shoe are disposed in a convenient forward position. A still further object of the invention lies in the provision of a structure by which to exert pressure of the shoe on the roll, together with a switch that is automatically operable to stop rotation of the roll when the shoe is in an opened position.

Other objects and advantages of the invention will be more fully understood and appreciated from a consideration of the following specification, taken in conjunction with the accompanying drawings; and in which

Fig. 1 is a front elevational view of an ironer embodying one form of the invention.

Fig. 2 is a plan view of the structure shown in Fig. 1;

Fig. 3 is an end view of the ironer showing, in outline, the general relationship of base, shoe, and roll;

Fig. 4 is an enlarged transverse vertical sectional view, taken substantially on the line 4—4 of Fig. 1;

Fig. 5 is a fragmentary elevational view showing details of the over-running clutch of the drive mechanism;

Fig. 6 is a substantially horizontal sectional view of the motor drive, being taken approximately on the line 6—6 of Fig. 4;

Fig. 7 is an enlarged transverse vertical sectional view taken substantially on the line 7—7 of Fig. 1, and shows the shoe in an opened or non-ironing position as distinguished from the position of the shoe in Fig. 4;

Fig. 8 is a vertical view, partly in section and

2

partly broken away, being taken as suggested by the line 8—8 of Fig. 7, and shows the shoe mounting, shoe operator, and switch control;

Fig. 9 is an enlarged vertical sectional view of the drive, transmission, and roll structure, being taken substantially on the line 9—9 of Fig. 3;

Fig. 10 is an enlarged fragmentary vertical sectional view of the roll transmission with the parts in slow drive position;

Fig. 11 is a view similar to Fig. 10 showing the transmission in a neutral position;

Fig. 12 is a further view of the transmission showing the parts in rapid drive position;

Fig. 13 is a fragmentary elevational view of the control for the transmission;

Fig. 14 is a fragmentary detail of the switch structure; and

Fig. 15 is a fragmentary detail of the clutch portion of the transmission, substantially as indicated at 15—15 of Fig. 12.

Referring more particularly to the drawing, the reference numeral 10 is employed to generally designate an ironer embodying one form of the present invention. The ironer comprises a base 11, roll 12, and shoe 13. The base 11 includes a rear wall 14, end walls 16, and a rounded front wall 17 that is of considerably less height than the rear wall 14 in order that the top wall 18 for the base will be at a considerably forward incline. For convenience in manufacture, as well as for the sake of appearance, the walls described as constituting the base 11 may be integral. Adjacent one end, the top 18 of the base 11 is formed with a raised portion 19 which serves as a seat and support for a casing 21. Directly beneath the portion 19, and fastened thereto in any suitable manner, is a drive housing 22. This housing, as may be seen in Fig. 4, includes a centrally located, downwardly directed, tubular boss 23. This boss continues above the top wall of the casing and may be of somewhat heavier proportions, as indicated at 24. It will be noted that the top wall of the housing 22 is at substantially the same incline as the portion 19 of the top of the base 11. A suitable bottom flange 26 of the housing 22 seats a corresponding flange of a lubricant containing pan 27, screws 28 serving to removably join these parts to provide a completely enclosed housing. Attached to one side wall 50 of the housing 22 in any suitable manner, as by studs 29, is a motor 31. This motor is disposed sufficiently toward the rear of the base 11 to be entirely contained therein, and a drive shaft 32 thereof projects through one side of the wall of 55 the housing 22 (see Fig. 6). A support 33 serves

as a bearing for one end of a shaft 34, on which is formed or secured a worm 36. The other end of the shaft 34 is coupled, substantially as shown, to the shaft 32 of the motor 31.

Press fitted into the boss 23 is a sleeve 37 which extends beneath the lower portion of the boss and well above the upper portion 24. The lower portion of the sleeve 37 mounts a gear wheel 38 that meshes with the worm 36. Any suitable means such, for example, as a washer and lock ring 39, prevents displacement of the wheel 38 in one direction with the hub 41 thereof in proximity with the lower end of the boss 23. Within the sleeve 37 is a drive shaft 42, suitable bushings 43 being provided adjacent the sleeve ends to mount this shaft. At its upper end, shaft 42 is fitted with a pin 44 which is received in the slotted end of the hub 46 of a pinion gear 47. To prevent downward displacement, the shaft is provided with a washer and lock ring 48, the washer deriving its support from the upper end of the sleeve 37. That portion of the shaft 42 extending beyond the lower end of the sleeve 37 is splined, as at 49, to mount a ratchet gear 50, the teeth 51 of which engage corresponding teeth 52 of the gear wheel 38. An expansion spring 53 encircles the hub portion of the gear 50, being held in a position to urge teeth 51 and 52 into engagement by means of a washer and clamp ring structure 54. The purpose of effecting drive from the motor 31 to shaft 42 through a clutch of this nature is to permit rotating the shaft 42 when the motor is inoperative. With particular reference to Fig. 4, it will be noted that the wheel 38 is so proportioned and located in the housing 22 that it extends well down into the pan 27. Thus, if suitable lubricant is placed in the pan, ratchet gear 50 will be substantially immersed in the lubricant and wheel 38 dip into such lubricant. Also lubricant is carried to the worm 36 and all moving parts within the housing.

The casing 21 may be contoured substantially as shown, and includes an interior integral sleeve 56 which receives the upper end of the sleeve 37. This sleeve depends from a web 57 and, as suggested in Fig. 9, the web constitutes the base of a bell-like upper portion 58 in which is housed the roll transmission. The pinion gear 47, described as being fitted onto the upper end of shaft 42, is located in the portion 58, an annular shoulder of the web 57 serving as an end thrust bearing therefor. One end of the portion 58 is open and terminates in an annular flange 59, to which a tubular member 61 is secured along a corresponding end portion 62, through screws 63. The roll 12 may be a conventional structure that includes a cylinder 64 with one or more interior reinforcing plates 66. A shaft 67 is attached to one or more of the plates 66 and projects through the tubular member into the portion 58. It will be evident from an examination of Fig. 9 of the drawing that the casing 21 and integral bell-like portion 58 serve, through the tubular member 61, shaft 67, and plates 66, to sustain the roll 12.

The end of the portion 58 remote from flange 59 is closed and formed with a central recessed boss 68. The end of the shaft 67 projecting into portion 58 has a splined area, indicated at 69, and terminates in a portion 71 that is located in the boss 68. Bushings 72, suitably located in the tubular member 61, together with boss 68, provide the entire bearing support for shaft 67. It will be noted that within the portion 58 a part 75

of the shaft 67 is not splined, and a gear 73 is mounted for free rotation on this portion. This gear meshes at all times with the pinion gear 47. Suitable means is provided to prevent axial displacement of gear 73 and, due to its contour, it is possible to locate a further gear 74 therewithin. Gear 74 includes a throw-out hub 76 that is movable axially of the splined portion 69. The teeth of this gear are adapted to mesh with the teeth of pinion 47. Two or more ribs 77 are formed in the interior portion of gear 73 and, when gear 74 is moved axially to a position to become disengaged from pinion 47, ribs 77 interfit recesses formed in an end portion 78 of the gear 74.

From the foregoing it is apparent that gear 73 is a free running gear in mesh at all times with the pinion 47 and, being of greater diameter than gear 74, constitutes the slow speed drive connection to the shaft 67 when the teeth of gear 74 are disengaged from the pinion 47, and this last mentioned gear has been moved axially of the splined portion 69 into engagement with gear 73. Conversely, when gear 74 occupies the position shown in Figs. 9 and 12 of the drawing, shaft 67 will be caused to rotate rapidly.

On the front of the casing 21 is located a lever 79 that serves to control high and low speed rotation of shaft 67 and roll 12. As shown in Fig. 4 of the drawing, the lever includes a circular body portion, on the inner face of which are three indentations or depressed areas 181, positioned ninety degrees apart. A reinforced portion 182 of the casing positions a ball check structure 183, the ball being receivable in one of the three recesses 181. The lever may be mounted on a squared end shaft 184 and held in place in any manner, as by a screw 186. The inner end of the shaft 184 is provided with an offset pin 187 which projects into a recess 188 in the throw-out collar 76. When the lever 79 is in the position shown in Fig. 13, gear 74 neither meshes with pinion 47 nor engages gear 73. Thus the legend adjacent the lever 79 would indicate neutral or pressing position of the ironer, since the roll 12 would not revolve but the ironer shoe could be brought into contact with the roll. Rotating the lever 79 to the position marked "Lo" causes gear 74 to engage gear 73 (see Fig. 10), whereas rotation of the lever 79 into the position marked "Hi" causes gear 74 to become engaged with the pinion 47 (see Fig. 12).

Centrally of the length of the base 11, and located toward the rear thereof, is a support 80. This support includes spaced, parallel walls 81 that are joined along flanges 82 to the rear wall 14 of the top 18. Adjacent the top 18 the walls are provided with ears 83 which project through suitable openings of the top 18, substantially as shown in Figs. 7 and 8 of the drawing. A channel-like shoe carrier 84 has sides 86 and the forward edges thereof are pivotally joined to the ears 83 by means of a pin 87. Above the base wall 88 of the carrier 84 are ears 89. Projections 91 are provided on the rear of the shoe 13 and pivotally joined to the ears 89 by a pin 92. This pin provides for vertical tilting or rocking of the shoe into full contact with the roller 12 when the shoe carrier has been moved into one extreme position. Adjacent the lower edges of the sides 86 of the carrier, substantially midway between pin 87 and wall 88, is located a shaft 93. The ends of this shaft extend beyond the sides 86 and are fitted with the ends of rods 94 of a shoe operator 96. A handle 97 is secured to the other ends of the rods 94 and completes this structure.

At a suitable point in the sides 86 of the shoe carrier, a pin 98 is located. This pin extends beyond the sides and is engageable by the rods 94 of the shoe operator 96 for the purpose of moving the carrier and shoe about the pivot pin 87 in a direction to engage roll 12.

Centrally, the shaft 93 is formed with a laterally extending yoke 99. Suitable openings 101 are provided in the arms of the yoke and mount a pin 102. This pin, as shown, has a bullet-like end 103 and a transverse opening located between the arms of the yoke into which the threaded end of a screw 106 projects. A rod 107 is carried by the walls 81 and provided with an opening through which the screw 106 projects. Between the yoke 99 and rod 107, the screw 106 mounts a compression spring 108. One end of the spring abuts the rod 107 and the other end abuts a washer 109, held in desired adjustment by a nut 111. The electrical circuit for the motor 31 includes a switch 112 which is carried by one of the walls 81 of the support 80. An arm 113, under suitable spring urging, extends into the path of movement of the bullet end 103 of pin 102.

The ironer above described is provided with a conventional cord which, when plugged into an outlet socket, brings the heating element up to ironing or pressing temperature. When an article to be pressed is applied to the roll, and the parts are in the position shown in Fig. 7, the operator grasps the handle 97, drawing it forwardly of the device. Such movement causes arms 94 to contact pin 98 and move shoe carrier forwardly to a position such that the shoe 13 contacts the roll 12, or the article on the roll. As the shoe approaches a position of contact with the roll, yoke 99 and screw 106 have been rotated to slightly beyond a straight line position and, during such movement, spring 109 has been placed under considerable compression. Thus, when yoke and screw are past center, this spring urges movement in a new direction which is transmitted to the shoe to the extent of providing the desired pressure upon an article on the roll, or the roll itself. This last position of the parts is clearly shown in Fig. 4. Additionally, as the yoke and screw swing into this new position, the bullet end 103 contacts and depresses arm 113 of the switch 112 and thus completes the circuit of the motor 31. Movement of the end 103 into position to complete the motor circuit through switch 112, occurs just before the shoe 13 contacts roll 12. Thus, at no time is the roll 12 left inadvertently stationary when the heated shoe is brought into contact with it. Of course, should the operator desire to press an article, it is possible to rotate the lever 79 to the position marked "Neutral," but under such circumstances the operator is obviously aware of the fact that the roll will not rotate. Following the pressing operation, the handle 97 is moved rearwardly, and when the yoke and screw 106 have passed center in the opposite direction, spring 109 will urge carrier 84 and shoe 13 into the position shown in Fig. 7.

From the foregoing it is evident that the invention discloses an ironing device of such proportions as to be readily portable, and one that includes advantages such as an automatic switch, constant lubrication, high and low speed roll drive, and over-running clutch. It will be understood, however, that variations or modifications of this structure may be made and are con-

templated insofar as they are within the spirit and scope of the annexed claims.

Having thus set forth my invention what I claim as new and for which I desire protection by Letters Patent is:

- 5 1. In an ironer, a base having a top wall downwardly inclined in the direction of an operator of the ironer, a drive casing extending substantially perpendicular to and being located at one end of said top wall, a rotatable roll carried by said casing, said casing serving to position said roll over the forward edge of said base whereby to facilitate its use.
- 10 2. In an ironer, a base having a top wall and further walls cooperating to incline a said top wall downwardly toward the front of said ironer, said walls together forming an enclosure substantially wedge shaped in cross section, a drive casing extending perpendicular to and located adjacent one end of said top wall, a rotatable roll carried by said casing extending parallel to and being located over the front edge portion of said top wall, a motor and drive mechanism mounted in said enclosure, and transmission means in said casing operatively associating said mechanism with said roll.
- 15 3. A portable type ironer comprising a base, one of the walls of said base being inclined downwardly in the direction of the front of said ironer and cooperating with other walls thereof to form a shallow enclosure substantially wedge shaped in cross section, a drive casing extending substantially perpendicular to said inclined wall and located adjacent one end of said base, a rotatable roll mounted on said casing and extending parallel to and overlying the front portion of said base, an ironer shoe movable into contact with said roll, means mounting said shoe, and drive means for said roll contained in its entirety within said base and said casing.
- 20 4. An ironer comprising a base having a top wall, further walls cooperating to incline said top wall downwardly toward the front of said ironer, said walls together forming a downwardly opening enclosure generally wedge shaped in cross section, a drive casing extending perpendicular to and located adjacent one end of said top wall, a rotatable roll carried by said casing extending parallel to and located over the front
- 25 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965

6. In a portable type ironer, a base having walls forming an enclosure, one of said walls being forwardly inclined, a drive casing extending perpendicular to and being mounted on the inclined wall of said base, a rotatable roll carried by said casing, drive mechanism in said casing projecting into said base, and a motor contained within said base having operative association with said drive mechanism.

7. In an ironer, a base having a top wall inclined downwardly toward the front of said ironer, a drive casing mounted on and extending perpendicular to said top wall, a rotatable roll carried by said casing, a shoe movable into contact with said roll, means mounting said shoe, multiple speed transmission means for said roll located in said casing, a motor in said base, driven means operatively connecting said motor and said transmission, switch means in the electrical circuit of said motor, and means operable by movement of said shoe to actuate said switch means.

8. In an ironer having a base, a drive casing mounted at one end of the top wall of said base, a rotatable roll carried by said casing, a shoe movable into contact with said roll, a lubricant containing housing in said base, a motor in said base adjacent to and having a driving shaft projecting into said housing, transmission means in said casing, a driven shaft disposed perpendicular to the top wall of said base, one end of said shaft having operative connection with said transmission means, the other end of said shaft projecting into said housing, a freely rotatable worm wheel on said shaft in mesh with a worm on said motor shaft, an overrunning clutch operable to transmit rotation of said wheel to said shaft, said wheel and clutch being so located as to be immersed in lubricant contained in said housing.

9. In an ironer, a base having a top wall inclined downwardly toward the front of said ironer, a drive casing mounted on and extending perpendicular to said top wall, a rotatable roll carried by said casing, a shoe movable into contact with said roll, means mounting said shoe, transmission means for said roll located in said casing, a motor in said base, driven means operatively connecting said motor and said transmission means, switch means in the electrical circuit of said motor, and means operable by movement of said shoe to actuate said switch means.

10. In an ironer, a base, the top wall of said

base being inclined downwardly toward the front of said ironer, said top wall and the other walls of said base cooperating to form a shallow enclosure substantially wedge shaped in cross section, a drive casing extending substantially perpendicular to and being located at one end of said top wall, a rotatable roll carried by said casing serving to position said roll over the forward edge of said base.

10 11. In an ironer, a base having a top wall inclined downwardly toward the front of the ironer, a drive casing mounted on and extending substantially perpendicular to said top wall, a rotatable roll carried by said casing, said casing serving to position said roll over the forward edge portion of said base, a lubricant containing housing in said base, a motor in said base adjacent to and having a drive shaft projecting into said housing, driven means connecting said roll with said driving shaft, said driven means being enclosed by said casing and said housing and being so organized as to be substantially parallel with the walls of said casing and inclined with respect to the base of said lubricant housing, that 20 portion of the driven means within said housing being, at least in part, immersed in lubricant in a manner to facilitate transmission of lubricant to other operative parts not so immersed.

ALLAN L. BRIGGS.
